UNITED STATES PATENT OFFICE

WILLARD J. LUFF, OF CLEVELAND HEIGHTS, OHIO

WASTE AND VENT FITTING

Application filed February 16, 1929. Serial No. 340,427.

The present invention relates, as indicated, to a waste and vent fitting, and the primary object thereof is to provide such a fitting which shall be of such dimensions as to be received conveniently within a wall, and which shall provide for inlets to the stack having their outer ends in alignment and having their inner ends so disposed as to prevent accumulation of soil or other solid matter within the stack. Further objects of the invention will appear as the description proceeds. To the accomplishment of the foregoing and related ends, said invention, then, consists of the means herein-
after fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a plan view of one embodiment of my invention; Fig. 2 is a side elevation thereof; Fig. 3 is a vertical section taken substantially upon the line 3—3 of Fig. 1; Fig. 4 is a vertical section taken substantially upon the line 4—4 of Fig. 1; Fig. 5 is a plan view of a second embodiment of the present invention; Fig. 6 is an elevation of the modification disclosed in Fig. 5; Fig. 7 is a vertical section taken substantially upon the line 7—7 of Fig. 5; and Fig. 8 is a vertical section taken substantially upon the line 8—8 of Fig. 5.

Referring more particularly to the embodiment disclosed in Figs. 1 to 4, it will be seen that I have provided a fitting indicated generally at 10 and comprising a stack section 11 adapted to be disposed with its axis in a vertical position. A pair of inlet branches 12 and 13 are formed on or secured to said stack section 11. The outer and inner ends respectively of the branch 12 are indicated at 14 and 15, while the outer and inner ends of the branch 13 are indicated respectively at 16 and 17. As will be clear, the outer ends 14 and 16 of the branches 12 and 13 are disposed in alignment with

each other, and in such a position that a vertical plane including their axes lies entirely outside of the stack section 11. It will further be noted that the axes of the inner ends 15 and 17 of the branches 12 and 13 meet each other in an acute angle opening toward said plane, and meet the axis of the stack section 11 in acute, upwardly opening angles. The inner ends 15 and 17 of the branches 12 and 13 are separated only by a thin fin of material indicated at 18.

The above described structure provides for discharge of waste material from fixtures through the branches 12 and 13 and into the stack section 11, such discharge entering the stack section at an angle to the axis thereof and in a downward direction. Inasmuch as the inner ends 15 and 17 of the two inlet branches are disposed adjacent each other instead of opposite each other, there is no possibility of a deposition within one of said branches of solid material in the stream entering the stack through the other of said branches.

It will be noted that the bottom wall 19 of the branch 12 inclines downwardly from its outer to its inner end while the top wall 20 thereof lies in a horizontal plane from end to end. Likewise, the bottom wall 21 of the branch 13 inclines downwardly from its outer to its inner end while the outer wall 22 thereof is included in a single horizontal plane. As is well known, a stream of liquid which has been given a cylindrical form will tend to maintain that form. Thus, a stream entering the branch 12 in a cylindrical form will tend to maintain that form as it flows downwardly through said branch and into the stack section. This will result in the creation of an open space adjacent the top wall 20 of said branch which space, communicating with the vent opening of the stack, will provide for proper venting of the fixture trap to prevent siphoning thereof.

Referring now to the embodiment disclosed in Figs. 5 to 8, it will be seen that I have provided a fitting indicated generally at 30 comprising a stack section 31 and a pair of inlet branches 32 and 33. The outer and inner ends of the branch 32 are indi-

cated respectively at 34 and 35 while the outer and inner ends of the branch 33 are indicated respectively at 36 and 37. As in the previous modification, the outer ends 34 and 36 of the two branches are disposed in alignment and in such a position that a vertical plane including their common axis lies entirely outside of the stack portion 31. The inner ends 35 and 37 are so disposed that 10 their axes meet each other in an acute angle opening toward the vertical plane above mentioned and meet the axis of the stack section 31 in upwardly opening acute angles, said ends being separated, where they open 15 into the stack section 31, only by a thin fin of material 38.

As in the previously described modification, the bottom walls 39 and 41 of said branches 32 and 33 are curved downwardly 20 from their outer to their inner ends, but in the present modification, the vent openings are not provided, the top walls 40 and 42 being likewise curved downwardly from their outer to their inner ends.

25 In certain of the claims, the terms "vertical" and "horizontal" have been used. It is to be understood that these terms are used in a relative sense only, being intended to define direction respectively aligned with 30 and perpendicular to the axis of the main section, it being understood that the main section is not necessarily mounted in an absolutely vertical position. The use of these terms in this relation has been necessitated 35 by the limitative effect of the term "parallel." A plane parallel to a line cannot, of course, include that line and it is not intended to limit all of the claims to a structure in which the plane including the axes 40 of the outer ends of the branches and parallel to longitudinal lines in the surface of the main section excludes the axis of said main section.

45 Other modes of applying the principle of my invention may be employed instead of the one explained, change being made as regards the mechanism herein disclosed, provided the means stated by any of the following claims or the equivalent of such stated 50 means be employed.

I therefore particularly point out and distinctly claim as my invention:

1. In a waste and vent fitting, a main portion 55 forming a passageway and having its lower end adapted for connection to a waste pipe section and its upper end adapted for connection to a vent pipe section, and a pair of waste inlet portions each forming a passageway and having their respective outer 60 ends adapted for connection to substantially horizontal waste pipe sections, the outer ends of the inlet sections having substantially a common axis, so positioned that if a cross section of the outer end of the inlet 65 passageway be projected axially said pas-

sageway will be approximately tangent to the main passageway, each of said inlet passages curving downwardly and inwardly toward the main passageway forming a substantially downwardly faced deflector surface 70 between the two inlet passages, the tops of said inlet passageways being approximately horizontal.

2. In a waste and vent fitting, a main portion forming a passageway and having its 75 lower end adapted for connection to a waste pipe section and its upper end adapted for connection to a vent pipe section, and a pair of waste inlet portions each forming a passageway and having their respective outer ends adapted for connection to substantially horizontal waste pipe sections, the outer ends of the inlet sections having substantially a common axis, so positioned that if a cross section of the outer end of the 80 inlet passageway be projected axially said passageway will intersect the main passageway, and the axis of each of said inlets being aligned outside of said main passageway, each of said inlet passages curving 85 downwardly and inwardly toward the main passageway forming a substantially downwardly faced deflector surface between the two inlet passages, the tops of said inlet passageways being approximately horizontal. 90

3. In a waste and vent fitting, a main portion forming a passageway and having its lower end adapted for connection to a waste pipe section and its upper end adapted for connection to a vent pipe section, and a 100 waste inlet portion forming a passageway and having its outer end adapted for connection to a substantially horizontal waste pipe section, the outer end of said inlet section having an axis, so positioned that if a cross 105 section of said outer end be projected axially said passageway will intersect the main passageway, the axis of said inlet being aligned outside of said main passageway, said inlet passageway curving downwardly and inwardly toward the main passageway forming a substantially downwardly faced deflector surface, the top of said inlet passageway being approximately horizontal. 110

Signed by me this 5th day of February, 115
1929.
